CLAIM

The ornamental design for a paraffin wax warmer, as shown and described.

DESCRIPTION

FIG. 1 is a top, front and left side perspective view of a paraffin wax warmer showing my new design; FIG. 2 is a top, front and right side perspective view thereof; FIG. 3 is a bottom, rear and right side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of portion 10 in FIG. 2; and, FIG. 11 is a top, front and right side perspective view showing the paraffin wax warmer in a use state.

The broken lines in the drawings illustrate portions of the paraffin wax warmer which form no part of the claimed design.

1 Claim, 11 Drawing Sheets
